UNITED STATES PATENT OFFICE.

BURR A. KENNEDY, OF CHICAGO, ILLINOIS.

HARVESTER.

SPECIFICATION forming part of Letters Patent No. 434,021, dated August 12, 1890.

Application filed May 12, 1890. Serial No. 351,580. (No model.)

To all whom it may concern:

Be it known that I, BURR A. KENNEDY, of Chicago, in the county of Cook and State of Illinois, have invented certain new and useful 5 Improvements in Harvesters, of which the following is a full description, reference being had to the accompanying drawings, in which—

Figure 1 is a rear end view of so much of the harvesting-machine as is necessary to 10 show my invention. Fig. 2 is a stubble-side sectional view of same, as if cut on the lines 22 of Fig. 1. Figs. 3 and 4 are details.

In the drawings, A is the main supporting-wheel; B, the grain-receiving platform; C and 15 C', the elevating devices, preferably constructed of two canvases, one above the other; but any form of elevator may be used in lieu thereof. These elevating devices are so supported as to be independent of each other at 20 the rear end in so far as to permit any grain which is carried by them to project rearward beyond them, my object being to make an elevator that may carry up grain or corn. The lowermost of the two elevators is supported upon the frame D, which in turn is 25 sustained by the post D', the frame and the post each being footed onto the lower framework of the machine in the usual manner. At the forward end of the machine is preferably a metallic plate E and a post E'. These form a support for the forward end of 30 the elevating devices.

In order to support the rear end of the uppermost elevating device, or in case a simpler grain-cover is used (as upon the old Marsh harvester) to support the latter, I provide a U-shaped support F, so clamped to the lower portions of the main harvester-frame at F' as to be properly sustained, and extend it 35 rearward and then curve it upward and forward and allow it to pass, preferably, underneath the seat-plank G. The seat-plank is secured to E' at its forward end, and is provided with clamps G' and G², which secure it to the 40 seat-board. As it is not always necessary to have the support F extend as far rearward as shown, I so adapt it that it may telescope, so 45 to speak, in its supports. In cutting corn it would be in the position shown in full lines 50 of Fig. 2, while in cutting grain it might be in the position shown by dotted lines in Fig. 2.

In Figs. 3 and 4 I show the structure of the clamping devices F'. A set-screw F³ extends through the bracket which is bolted to the rear platform-sill, and in this is a gas-pipe H, 55 bolted at the front in the bracket F². Into this gas-pipe the U-shaped bar F may slide, and by loosening the set-screw F' and the clamps G' and G² it may be slid to any position required. 60

In order to prevent the support F from moving sidewise, I provide a brace I, which I preferably make in two parts, as I and I', and connect them by any suitable device, as I². This brace is connected to the post D', 65 and it will be readily understood that its length may be varied to correspond with the various positions to which the support F is adjusted. I do not limit myself to the use of this brace, because the parts can be made so 70 stiff as to not require it, but would necessarily be somewhat heavier. I therefore show it.

J is an extension of the plane of the lower elevator, but constructed of boards or sheet-iron, provided for the purpose of guiding long 75 grain or cornstalks in their passage upward.

I have shown H to be a tube. This is not essential, as it may be a flat bar and the bar F clamped to it precisely as the said bar is clamped to the board G; but I prefer the 80 pipe.

I have shown special means for adjusting the length of the brace composed of the parts I and I'—namely, the clamp I²; but I do not limit myself to such construction, nor do I 85 limit myself to a brace the length of which can be varied, because the same purpose would be served if braces of various lengths were used, and I should consider them equivalents.

I do not claim supporting the seat-board 90 upon any U-shaped support, as F, and connecting thereto the upper elevator-frame for the purpose of support, as this construction, as well some features which I have shown but not described, is the invention of John F. 95 Steward.

What I claim as my invention, and desire to secure by Letters Patent of the United States, is—

1. The combination of the elevators C and C' and the adjustable support F, substantially as described. 100

2. The combination of the seat-board support G, the main frame, and the adjustable support F, substantially as described.
3. The combination of the main frame, the seat-support G, and the elevators C and C', and adjustable support F, substantially as described.
4. The combination of the main platform having the pipe or its equivalent H, the support G, for sustaining the elevating-canvas C', and the support F, adapted to telescope relative thereto in its adjustment and be held, substantially as described.
5. In a harvester, the combination of the

adjustable seat-board support F and the adjustable brace II', substantially as described. 15

6. In a harvester, the combination of the support F', provided with the set-screw F³ or its equivalent, and the adjustable U-shaped seat-board support, substantially as described. 20

7. The combination of the elevator C and extended platform J, the elevator C', and the U-shaped support adjustable in its position fore and aft, substantially as described.

BURR A. KENNEDY.
